UNITED STATES PATENT OFFICE

SIMON COOPER, OF BROOKLYN, NEW YORK

ELECTRICAL SOSTENUTO PIANO

Application filed March 25, 1927, Serial No. 178,207. Renewed March 14, 1931.

This invention relates to electrical sostenuato operation of pianos.

One of the objects of the present invention is to provide a method of and apparatus for simply and satisfactorily overcoming a previous difficulty, that of properly timing the energization of the string magnet with the movement of the string toward such magnet. The magnetic pluck, I have found, should occur while the string is moving toward the magnet, while, on the other hand, the magnet should be at lowest ebb of energization during movement of the string away from the magnet. Furthermore, I have found that the magnetic pluck must occur often and with slight force, as distinguished from a rather infrequent pluck of considerable force; to avoid any derangement of the natural formation of the loops and nodes making the musical note. As I state in my copending application Ser. No. 178,204, filed March 25, 1927, wherein the general principles underlying the present invention are described, and somewhat analogous invention structures are described and claimed, I have also found that excellent results are obtained when the rapidly occurring current fluctuations through the magnet, each giving rise to a pluck on the string toward the magnet, and each occurring in timed relation to and as the result of a vibratile movement of the string relative to a current pulsator or controller for the magnet, occur at a frequency representing a sub-multiple of the fundamental frequency of vibration of the string.

The object foregoing, I attain in the present case by the use of means giving special support and connection for the pulsator relative to the vibrating musical string, and by incorporating instrumentalities for adjusting the pulsator relative to the support and if desired for also or alternatively adjusting a connection part, the first mentioned adjustment being preferably an adjustment of the pulsator angularly around the string; as I have discovered that such adjustments require comparatively little skill and time in order to set the pulsator to energize the magnet at the critical moment.

Another object is to provide an improved type of pulsator of extremely simple and compact type, of reliable operation, and capable when employed with the new mount of coacting therewith in a specially advantageous manner in attaining the object of the invention first stated.

Various other objects and advantages of the invention will be specifically pointed out or apparent hereinafter in the course of a description of a preferred one of the various possible forms of the invention as shown in the accompanying drawings; it being understood, of course, that such form is merely illustrative of one combination and arrangement of parts calculated to attain the objects of the invention, pursuant to present preference, and hence the detailed description of such form now to be given is not to be taken as at all defining or limiting the invention itself.

In the accompanying drawings:

Fig. 1 is a diagrammatic view illustrating, together with one form of pulsator and circuit, one form of mount according to the invention.

Fig. 2 is an enlarged view, showing, in full lines, the piano string and said pulsator and its mount in side elevation, and certain parts of the piano in vertical section.

Fig. 3 shows, in full lines, the parts of Fig. 2 in top plan except as indicated by the section line 3—3 of Fig. 2.

Fig. 4 is an enlarged axial section of the pulsator of Fig. 2.

Fig. 5 is a face view of a transverse element in said pulsator of Fig. 2.

Fig. 6 is a view similar to Fig. 4, showing another form of pulsator.

Similar reference characters refer to similar parts throughout the several views of the drawings.

In Fig. 1, one of the piano strings is indicated at 10, stretched over the bridge pieces 11 and 12. 13 indicates the electromagnet for vibrating the string by magnetic pluck, and 14 the pulsator for controlling said magnet, said pulsator being located in a circuit with the magnet, which circuit includes a suitable source of energy 15 and a switch 16 operated

by the piano key 17 when the latter is depressed.

The hammer for the string is conventionally indicated at H.

As shown most clearly in Figs. 2 and 3, wherein the upper bridge 11 and bearing-bar B appear more in detail but still somewhat conventionally, the pulsator may be positioned at about opposite the upper bridge, by means including a spring strip or rod member 26, desirably a comparatively heavy wire bent as shown, and suitably embedded or anchored at its end 26' in the piano body.

Comparing Figs. 2, 3, 4 and 5 with Fig. 6, it will be seen that the two forms of pulsator illustrated are of identical construction except that the element 28, which is of some non-resonant material as felt or wool, is omitted as a spacing element between electrode 18 and the preferably more massive companion electrode 19. Except for the difference just noted, each pulsator shown includes these two electrodes, a common sheath or envelope 25 holding both electrodes, which sheath is also of non-resonant material as felt or wool, and a mass or collection C of conducting material in fragmentary condition between the opposed faces of the electrodes. The sheath or envelope 25 in the present case acts not only as a non-resonant mount for the more massive electrode, but also as a carrier for both electrodes and the contents of the chamber 27 formed between their opposed faces. In order to more securely bind the parts together, and yet keep undisturbed the generally non-vibratile mount desirable for the two electrodes, the pulsator may be bound loosely, as indicated, by a strand or strands of wool yarn 25a or the like.

To attain the advantages described and claimed in my copending application above identified, of having self-renewing contact faces, the collection C is loose within chamber 27, whether or not the spacing element 28 is in said chamber, as indicated at 27' in Figs. 4 and 6. When said spacing element is present the collection C is broken up into groups and these groups are loose sub-collections of fragmentary conducting material in each of the pockets marked off in said chamber by the through openings in said element 28 as indicated at 28a in Fig. 5. Referring to the form of Fig. 6, it will be understood that here the collection of conducting material acts solely as the spacing element for the electrodes; such collection being capable of so acting even when loose in the chamber 27, as will be understood.

The new mount for the pulsator includes as above the spring rod or wire member 26. Such member has preferably a double or reversed rather deep intermediate goose-neck portion as shown, and presents an upwardly extending terminal length beyond and some

distance away from the piano strings. The electrode 18 of the pulsator has screwed therein a threaded stud 29, this stud carrying a pair of nuts which may be screwed up tight to mount the electrode 18 and hence the whole pulsator on said terminal length of the bent wire member 26. One of these nuts, as clearly indicated in Fig. 2, may have a straight half-round groove cut in its end facing the other nut, so that when the latter nut is tightened up the pulsator may be held with its axis substantially horizontal. Such nuts, nevertheless, may be used obviously to vary the position of the pulsator on the support, as desired, for instance as shown in broken lines in Fig. 4.

The new mount also preferably includes a fine strand of wire or the like, as indicated at 30, such wire being preferably of metal. This strand is fastened at one end to the string near or about its bridge support 11a, and at the other end to the bent rod member 26 not far from the securing nuts for the pulsator.

In operation, when the string 10 vibrates, it transmits motion to the long terminal up-standing end of the member 26, and thence to the electrode 18.

Since electrode 19 is suspended in an envelope which has little resonance and relatively slight "recoverance", it is to a great extent subject to the inertia of its mass. Thus, when the electrode 18 is put into rapid oscillatory motion, the electrode 19 is comparatively lethargic in its movement, and so the carbon granules between the two electrodes are caused to vary in electric conductivity, slightly, yet very rapidly, and with a rate of current fluctuation rather close than otherwise to the rate of vibration of the string; all as explained fully and claimed, in my co-pending application above identified.

The presence of the member 26 or an equivalent, however, rather intensifies this rapidity of current fluctuation, while failing to act, in spite of its own natural period of vibration, deleteriously in regard to the true sostenuto desired, and while permitting other adjustments in aid of such sostenuto. When the natural pitch of vibration acts distortingly on the sostenuto, the phase or amplitude of vibration of the member 26 is corrected by changing the point of connection of the strand 30 on said member, as for instance indicated at 30a and 30b in Fig. 2. When the vibration of the electrode 18 is not properly timed with that of the string 10, the point of connection of the strand 30 on the string itself may be varied. I have found that both these troubles may be overcome in most cases by maintaining the point of connection between the strand and the string, and thus solely by changing the point of connection between the strand and the member 26; particularly when the pulsator is angularly adjusted about the upstanding

terminal length of said member, which is an especially easy adjustment to make. Often, this pulsator adjustment alone results in quick co-ordination of the various elements for true sostenuto.

In practice, it is sometimes particularly difficult to insure that the pulsator will vibrate with the same frequency as the high-tension musical strings in the treble; but I have found that even in the case of such strings, the various adjustments provided by the present invention allow for comparative ease in producing a pitch of vibration in the pulsator which is a sub-multiple of that of the string. Then, as described and claimed in my copending application above identified, the lethargic movement of the electrode results in a smooth undulatory electric current in the magnet which tends to avoid disturbance in the natural formation of the musical string, and the result is a sweet, mellow musical note sustained as long as desired, in other words, true sostenuto.

I have found that when the pulsator has been adjusted for one particular note of the piano, this adjustment may serve for control of the adjoining notes on both sides; and it is only necessary to make the proper circuit connections to the magnets for these notes, say by placing the latter magnets in parallel in a common circuit with the pulsator, and to connect, as shown at 31 and 32 in Fig. 3, other strands to the pulsator, and in this way have the one pulsator control two or more notes of the piano, the magnets for such other strings being in circuit with their respective switches 16 and connected in multiple with battery 15.

Inasmuch as many changes could be made in the above constructions, and many apparently widely different embodiments of my invention could be made without departing from the scope thereof, it is intended that all matter contained in the above description or shown in the accompanying drawings shall be interpreted as illustrative and not in a limiting sense.

It is also to be understood that the language contained in the following claims is intended to cover all the generic and specific features of the invention herein described and all statements of the scope of the invention which, as a matter of language, might be said to fall therebetween.

What I claim is:

1. In a device of the kind described, a vibratile string, a resilient support mounted to vibrate in sympathy with the string, a pulsator, means for coupling the pulsator to the string for vibration therewith and including said support, a magnet in circuit with the pulsator and adapted to actuate the string, and an auxiliary means for coupling the pulsator to the string for vibration therewith including a mechanical con-

nnection between the pulsator and its support, and the string.

2. In a device of the kind described, a vibratile string, a resilient support mounted to vibrate in sympathy with the string, a pulsator, means for coupling the pulsator to the string for vibration therewith and including said support, a magnet in circuit with the pulsator and adapted to actuate the string, and an auxiliary means for coupling the pulsator to the string for vibration therewith including a direct mechanical connection between said support and the string.

3. In a device of the kind described, a vibratile string, a resilient support mounted to vibrate in sympathy with the string, a pulsator, means for coupling the pulsator to the string for vibration therewith and including said support, a magnet in circuit with the pulsator and adapted to actuate the string, and an auxiliary means for coupling the pulsator to the string for vibration therewith including a direct mechanical connection between said support and the string, said connection being a wire kept taut by tension.

4. In a device of the kind described, a vibratile string, a resilient support mounted to vibrate with the string, a pulsator bodily carried by said support at a distance from the string, said pulsator including a plurality of spaced and relatively movable electrodes, and means for varying the action of said electrodes by angularly adjusting the pulsator on said support.

5. In a device of the kind described, a vibratile string, a resilient support mounted to vibrate with the string, a pulsator bodily carried by said support at a distance from the string, said pulsator including a plurality of spaced and relatively movable electrodes, and means for varying the action of said electrodes by rotating the pulsator about an axis substantially parallel to the axis of the string when quiescent.

6. In a device of the kind described, a vibratile string, a resilient support mounted to vibrate with the string, a pulsator bodily carried by said support at a distance from the string, said pulsator including a plurality of spaced and relatively movable electrodes, and means for varying the action of said electrodes by rotating the pulsator in a substantially horizontal plane.

7. In a device of the kind described, a vibratile string, a resilient support mounted to vibrate with the string, a pulsator bodily carried by said support at a distance from the string, said pulsator including a plurality of spaced and relatively movable electrodes, and means for varying the action of said electrodes by rocking the pulsator about a point spaced from the string.

8. In a device of the kind described, a vibratile string, a resilient support mounted to vibrate with the string, a pulsator bodily

carried by said support at a distance from the string, said pulsator including a plurality of spaced and relatively movable electrodes, and means for varying the action of said electrodes by changing the angular relation of the space between said electrodes and the plane of vibration of the string.

9. In a device of the kind described, a vibratile string, a resilient support mounted to vibrate with the string, a pulsator on said support, and means for coinciding the action of the magnet and the vibration of the string, said means including a means for varying the position of the pulsator on the support, and a mechanical connection between the pulsator and its support, and the string, said connection being adjustable along the length of the string.

10. In a device of the kind described, a vibratile string, a resilient support mounted to vibrate with the string, a pulsator on said support, and means for coinciding the action of the magnet and the vibration of the string, said means including a means for varying the position of the pulsator on the support, and a mechanical connection between the pulsator and its support, and the string, the support having an elongate vibratile portion spaced from the string and said connection being adjustable along the length of said portion.

11. The device defined in claim 8, wherein said connection is also adjustable as to its end nearer the pulsator and support.

12. In a device of the kind described, the combination of a vibratile string, a pulsator, means including a vibratile support itself supported on a part other than the string but for vibrating the pulsator with the string, and means associated with the string for preventing distortion from the inherent pitch of vibration of the first-mentioned means.

13. In a device of the kind described, the combination of a vibratile string, a pulsator, means including a vibratile support, a flexible connection between the support and the string for vibrating the pulsator with the string, and means associated with said support for preventing distortion from the inherent pitch of vibration of said support.

14. In a device of the kind described, the combination of a vibratile string, a pulsator, means including a vibratile support for vibrating the pulsator with the string, and means for preventing sostenuto distortion from the inherent pitch of vibration of a component of the first-mentioned means, the distortion preventing means including an instrumentality for adjusting the pulsator relative to the first-mentioned means, said support being mounted non-contactingly of the string.

15. In a device of the kind described, the combination of a vibratile string, a pulsator,

means including a vibratile support for vibrating the pulsator with the string, and means for preventing sostenuto distortion from the inherent pitch of vibration of a component of the first-mentioned means, the distortion preventing means including an instrumentality for permitting a variable mechanical connection between the first-mentioned means and the pulsator, and the string.

16. In a device of the kind described, a vibratile string, a resilient member supported out of contact with the string but to vibrate in sympathy therewith, a pulsator bodily carried by said resilient member, and a magnet in circuit with the pulsator for operating the string for sostenuto.

17. In a device of the kind described, a vibratile string, a resilient member supported out of contact with the string but to vibrate in sympathy therewith, a pulsator bodily carried by said resilient member, a magnet in circuit with the pulsator for operating the string for sostenuto, and means for timing the energization of the magnet to pluck the string during movements of the latter toward the magnet and for otherwise insuring substantially undistorted sostenuto.

18. In a device of the kind described, a vibratile string, a resilient member supported out of contact with the string but to vibrate in sympathy therewith, a pulsator bodily carried by said resilient member, a magnet in circuit with the pulsator for operating the string for sostenuto, and means for insuring that the rate of vibration of the pulsator will be a sub-multiple of the rate of vibration of the string.

19. In a device of the kind described, vibratile strings of two different notes, a magnet associated with each string, a pulsator for actuating both magnets, and a mount for the pulsator including a supporting member secured to a part of the piano other than a string thereof and also including a separate mechanical connection from said mount to each of the two strings.

20. In a device of the kind described, vibratile strings of two different notes, a magnet associated with each string, a pulsator for actuating both magnets, and a mount for the pulsator including a supporting member secured to a part of the piano other than a string thereof and also including a separate strand of wire from said mount to each of the two strings.

21. In a device of the kind described, vibratile strings of two different notes, a magnet associated with each string, a pulsator for actuating both magnets, and a mount for the pulsator including a supporting member and a separate, mechanical connection from said mount to each of the two strings, said member being resilient and said connections

being strands more flexible than said member.

22. In electrical sostenuto for pianos, the method of utilizing a pulsator operated by the vibration of a string and a magnet energized by such pulsator to sustain the vibration of the string, which involves imparting vibrations to the pulsator from the string through a path including a part of the piano 10 other than the string and simultaneously imparting vibrations to the pulsator through a path exclusive of said piano part.

23. The method defined in claim 21, wherein the pulsator vibrations are further modified in aid of true sostenuto by modifying the relation of one of said paths to the line 15 of extension of the string.

24. The method defined in claim 21, wherein the pulsator vibrations are further modified in aid of true sostenuto by modifying the relation of one of said paths angularly 20 relative to the plane of vibration of the string.

25. The method defined in claim 21, wherein the pulsator vibrations are further modified in aid of true sostenuto by modifying the relation of one of said paths to the line 25 of extension of the string, and by modifying a line of extension of one of said paths in a plane substantially perpendicular to the line 30 of extension of the string.

In testimony whereof I affix my signature.
SIMON COOPER.
